UNITED STATES PATENT OFFICE.

WILLIAM H. LA BAUVE, OF WEST COLUMBIA, TEXAS.

AUTOMATIC CUT-OFF.

1,370,455.

Specification of Letters Patent.

Patented Mar. 1, 1921.

Application filed May 8, 1920. Serial No. 379,779.

To all whom it may concern:

Be it known that I, WILLIAM H. LA BAUVE, citizen of the United States, residing at West Columbia, in the county of Brazoria, and State of Texas, have invented certain new and useful Improvements in Automatic Cut-Offs, of which the following is a specification.

This invention relates to new and useful improvements in an automatic cut off.

One object of the invention is to provide a device of the character described whereby the motive fluid may be automatically cut off.

With the above and other objects in view the invention has particular relation to certain novel features of construction, operation and arrangement of parts an example of which is given in this specification and illustrated in the accompanying drawings, wherein:—

Figure 1 shows a side elevation of a steam engine with the device attached thereto.

Fig. 2 shows a partial plan view of the device.

Fig. 3 shows a side view of a ratchet wheel employed.

Fig. 4 shows an edge view thereof.

Fig. 5 shows a partial side view and,

Fig. 6 shows a side view of another form of the device.

Referring now more particularly to the drawings, wherein like numerals of reference designate similar parts in each of the figures, the numeral 1 refers to the engine support, the numeral 2 designates the engine, the numeral 3 refers to the fly wheel, and the numeral 4 refers to the drive shaft whereon said fly wheel is fixed. The shaft 4 has a crank 5 and a connecting rod 6 connected at one end to the piston 7 and at its other end, to the crank 5. The shaft 4 has the usual eccentric, (not shown) which operates the valve rods 9, 9 through the ring 10, which surrounds the eccentric and which is connected to said rods.

The numeral 11 refers to the steam pipe through which steam is admitted, under pressure, to the engine cylinder, and this pipe is controlled by a suitable cut off valve 12, of conventional form. This valve has a stem 13 which projects through a suitable bearing in the valve casing, and has a ratchet wheel 14 fixed thereon.

A ring 15 is keyed on the shaft 4 outside of said eccentric, and a swinging arm 16 is

pivoted at its inner end to the periphery of the ring 15. The outer end of this arm carries a weight 17 and there is a lug 18 carried by said arm and overturned at right angles thereto. The arm is normally held against a projecting stop 19, carried by the ring, by the tension of a pull spring 20, which is attached at its respective ends to the arm and to a lug 21 carried by the ring 15 behind said stop.

Fixed upon the shaft 4 is an eccentric 22 around which works the eccentric ring 23 and one end of the rod 24 is connected to this ring. The other end of this rod carries the dog 25 which is pivoted thereto. A sliding plate 26 fits against the rod 24 and has long slots 27, 27 therethrough and the pins 28, 28 are secured to the rod and project through said slots and form bearings for said plate. A link 29 is connected, at one end, to an ear which upstands from the dog 25, and at its other end it is connected to the near end of the plate 26. The rod 24 and the sliding plate 26 have the respective lugs 30 and 31 upstanding therefrom which are connected by means of a pull spring 32 which operates to normally hold the other end of the plate 26 against the free end of the trigger 33 which is pivoted to the rod 24. This trigger has an overturned lug 35 which is integral therewith and which is provided for a purpose to be hereinafter stated. The dog 25 and the adjacent end of the rod are pivoted to the lower end of the link 36. This link has a slot 37 in its upper end forming a long bearing on the valve stem 13 and the pull spring 38 is attached at one end to said stem and at its other end it is attached to said link near its lower end.

In operation the fly wheel turns in the direction indicated by the arrow in Fig. 1 and as it speeds up the arm 16 is relatively retarded by its inertia, and being connected eccentrically with respect to the shaft 4, as it is retarded the lug 18 is carried farther out from the center of the shaft 4 and will eventually reach the lug 35 and disengage the trigger 33 from the adjacent end of the plate 26, as shown in Fig. 5, and thereupon the spring 32 will retract said plate, as shown in Fig. 5. This will operate through the link 29 to carry the dog 25 into engagement with the ratchet wheel 13 and as the rod 24 continues to operate said ratchet wheel 13 will be turned by successive partial rotations, thus turning the stem 13 and closing the

valve 12 which will cut off the steam from the engine. The momentum of the fly wheel 3 will cause it to continue to rotate for a time, and the dog 25 being in engagement 5 with the ratchet wheel, but said valve being closed so that it is not possible for the ratchet wheel to turn farther, the result will be that the link 36 will be pulled downwardly, overcoming the tension of the 10 spring 38 and this will permit the lower end of the dog 25 to swing around, following the course of the arrow indicated in Fig. 5 and thus preventing the breakage of the parts due to the rotation of the fly wheel after the 15 steam has been cut off.

Before the engine is again started the latch 35 is again manually engaged behind the adjacent end of the plate 26, as is shown in Fig. 1, which will operate to set the device in position or action before the engine 20 is again started.

In the form shown in Fig. 6 the valve actuating rod is shown in two sections 24' and 26', one end of the latter of which is 25 pivoted to the free end of the valve arm 39 which is fixed upon the outer end of the valve stem 13. These sections have the respective slots 40 and 41 therethrough through which the respective pins 42 and 30 43, secured to the other sections, operate. The sections 24', and 26' are yieldably connected by means of the pull spring 44 which is secured at its respective ends to said re-

spective sections. The section 24' operates through a bearing 45 and has the depending 35 lug 46 with which the lug 18 engages, when the engine speeds up. This operates to withdraw the actuating rod and to close the valve and after the valve is closed the spring 44 will yield to permit the lug 18 to pass the lug 46 without breakage of parts. After the lug 18 has released the lug 35 and 46, as the case may be, the spring 20 will swing the arm 16 around into its original position against the stop 19. 40 45

What I claim is:

In a device of the character described in combination an engine having a steam inlet pipe, a throttle valve controlling said pipe, a rotatable member driven by the engine, 50 means connected to and driven by said member and normally out of engagement with the valve, and a second means eccentrically mounted on said member which is carried, by its inertia, into engagement with said 55 first mentioned means when said member has attained a predetermined speed, whereby said first mentioned means is actuated into engagement with the valve to close the same.

In testimony whereof I have signed my 60 name to this specification in the presence of two subscribing witnesses.

WILLIAM H. LA BAUVE.

Witnesses:

CLAY MORRA,
JAS. S. LUMPKIN.
